(57) **CLAIM**

The ornamental design for a robot arm for interventional surgery, as shown and described.

DESCRIPTION

The patent or application file contains at least one drawing executed in color. Copies of this patent or patent application publication with color drawing(s) will be provided by the Office upon request and payment of the necessary fee.

1. Robot arm for interventional surgery

Fig. 1.1 is a front, right perspective view of a robot arm for interventional surgery showing our new design;

Fig. 1.2 is a back, left perspective view thereof;

Fig. 1.3 is a front elevation view thereof;

Fig. 1.4 is a back elevation view thereof;

Fig. 1.5 is a left-side view thereof;

Fig. 1.6 is a right-side view thereof;

Fig. 1.7 is a top plan view thereof; and

Fig. 1.8 is a bottom plan view thereof.

The broken lines in the drawings depict portions of the robot arm for interventional surgery that form no part of the claimed design.
